UNITED STATES PATENT OFFICE.

LOUIS J. HIRT, OF BROOKLINE, MASSACHUSETTS.

GAS-ENGINE.

SPECIFICATION forming part of Letters Patent No. 620,926, dated March 14, 1899.

Application filed October 30, 1897. Serial No. 656,894. (No model.)

To all whom it may concern:

Be it known that I, LOUIS J. HIRT, residing in Brookline, in the county of Norfolk and State of Massachusetts, have invented an Improvement in Gas-Engines, of which the following description, in connection with the accompanying drawings, is a specification, like letters and figures on the drawings representing like parts.

This invention relates to gas-engines, and has for its object to provide an engine which is capable of operating as a constant-pressure engine and of being automatically converted into a variable-pressure engine by diminution of the pressure of the gas employed to run the engine. In accordance with this invention the engine may be started under a constant pressure and run as a constant-pressure engine, gas being admitted and exploded at each stroke of the engine until the engine is running in the desired or proper manner, and when it is so running the supply of gas and air at a reduced pressure may be admitted to the engine-cylinder, and the engine responds to the diminution in the pressure of the gas and automatically converts itself into a variable-pressure engine in which the gas is exploded once for every two complete reciprocations of the piston.

In the present instance I have embodied my invention in a double-acting engine of the well-known "Corliss" type in order that the operation of the engine may be clearly shown and easily understood; but I do not desire to limit my invention to this particular type of engine, as it can be embodied in other well-known forms of engines.

In accordance with this invention the admission and exhaust valves for the engine are adapted to be operated at each stroke of the piston when the latter is running under a constant pressure, but are controlled automatically, as will be described, by the pressure of the gas, so as not to be operated on alternate strokes of the piston when the engine is running under a variable pressure of the gas. The gas-admission valves are also further controlled by a governor which automatically regulates the amount of gas admitted into the cylinder according to the speed of the engine. The engine is provided with igniters for the gas, which are auto-

matically controlled, as will be described, so as to effect an explosion of the gas at each reciprocation of the piston when the engine is running under constant pressure and at alternate reciprocations of the piston when the engine is running under a variable pressure. These and other features of this invention will be pointed out in the claims at the end of this specification.

Figure 1 is a top or plan view of a gas-engine embodying this invention; Fig. 2, a front elevation of the engine shown in Fig. 1; Fig. 3, a detail, on a larger scale and in front elevation, of the right-hand portion of the engine shown in Fig. 2; Fig. 4, a sectional detail on the line 4-4, Fig. 1; Fig. 5, a detail of the valve-operating mechanism to be referred to; Fig. 6, a top or plan view of the mechanism shown in Fig. 5; Figs. 7, 8, and 9, details to be referred to, Fig. 9 being a section on the line 9-9, Fig. 8; Figs. 10 and 11, details to be referred to; Fig. 12, a sectional detail, on an enlarged scale, on the line 12-12, Fig. 1; and Figs. 13, 14, 15, 16, 17, 18, and 19, details to be referred to, Fig. 15 being a section on the line 15-15, Fig. 6, looking toward the right.

In the present embodiment of this invention A represents the cylinder of the engine, provided with water jackets or spaces A' at its ends and around its body portion and with the piston A², (see dotted lines, Fig. 1,) having its piston-rod A³ joined by the connecting-rod A⁴ to a crank-pin A⁵ on a crank or disk A⁶, fast on the main shaft A⁷, having bearings in the base or framework A⁸. The cylinder A has secured to it, preferably on one side at its opposite ends, two sets of valve-casings a a' a² a³, the casings a a² containing the gas-admission valves a⁴ a⁵ (see Fig. 3) and the casings a' a³ containing the exhaust-valves a⁶ a⁷. The valves a⁴ a⁵ a⁶ a⁷ are preferably made as piston-valves co-operating with suitable seats in their respective valve-casings and provided with valve-rods a⁸ a⁹ a¹⁰ a¹¹ a¹², (see Fig. 3,) which are extended up through the heads or upper ends of the valve-casings and each of which is secured to an actuating mechanism, as will be described. Inasmuch as the actuating mechanisms for all the valves are the same, I will specifically describe the construction of but

one, which may be supposed to be that which operates the admission-valve a^4 . The actuating mechanism referred to consists, essentially, of a rock-shaft a^{20} , (see Figs. 5, 6, and 15,) having a bearing in a standard or upright a^{21} , erected upon the head of the valve-casing. The rock-shaft a^{20} at one end has fast on it a crank or arm a^{22} , having its end rounded or provided with a ball a^{23} , (see Figs. 6, 18, and 19,) which enters a slot a^{24} in the end of a bar or rod a^{25} , fastened to the valve-stem a^8 , so that when the rock-shaft a^{20} is moved in the direction indicated by the arrow 20, Fig. 5, the valve a^4 will be lifted from its seat, so as to permit the gas or gas and air to pass into the cylinder A. The rock-shaft a^{20} at its opposite end has fast on it a second crank or arm a^{30} , carrying a bolt a^{31} , provided with a square or other than round head a^{32} , (see dotted lines, Figs. 6 and 16,) which is adapted to be engaged by an arm a^{34} , provided with a latch or hook a^{35} and fast on a shaft a^{36} , having bearings in a hub a^{37} , attached to a crank or arm a^{38} , extended from the sleeve or hub a^{39} , loosely mounted on the end 2 of the bearing-hub for the rock-shaft a^{20} and provided with a second arm or crank a^{40} . The sleeve or hub a^{39} is adapted to be operated by an eccentric a^{41} on the main shaft A⁷, and which eccentric for the purpose of this invention I prefer to designate as the "main" eccentric. The eccentric a^{41} , as shown in Fig. 2, is joined by a rod a^{42} to a lever a^{43} , pivoted to the framework and connected by a rod a^{44} to a wrist-plate a^{45} , pivotally mounted on a stud or bracket a^{46} , attached to the side of the cylinder A. (See Fig. 1.) The wrist-plate a^{45} is joined by a link or rod a^{47} to the crank or arm a^{40} . From the above description it will be seen that at each revolution of the main shaft A⁷ the crank or arm a^{40} of the sleeve a^{39} will be actuated to lift the valve a^4 if the latch or hooked arm a^{34} is in position to engage the head a^{32} of the bolt a^{31} . When the engine is running as a constant-pressure engine at normal speed, the latch or arm a^{34} is in proper position at all times to engage the head a^{32} of the bolt and lift the valve once for every revolution of the main shaft, and consequently lift the valve once for every complete reciprocation of the piston A². The latch-arm a^{34} is held in its proper position until positively removed therefrom by tripping devices or mechanisms, as will be described, by means of a spring a^{50} , attached at one end to the crank or arm a^{38} . (See Fig. 5.)

In order to enable the engine to be automatically converted from a constant-pressure engine into a variable-pressure engine, provision is made by which the latch is disengaged on every alternate revolution of the main shaft A⁷. This result is effected in the present instance by providing the rock-shaft a^{20} with a crank or arm a^{51} , extended downward toward the rock-shaft a^{20} , so that the crank or arm a^{51} may be engaged at the proper time by suitable cams, as will be described, so as to

turn the rock-shaft a^{20} in its sleeve a^{37} and remove the latch-arm a^{34} from its operative position with relation to the head of the bolt a^{31} . 70

Referring to Figs. 5, 6, and 15, the bearing-hub, supporting the rock-shaft a^{20} , is made of different diameters to form bearings 2 3 for the sleeve a^{39} and a lever a^{55} and for a sleeve or hub a^{56} , provided with a crank or arm a^{57} , 75 the sleeve a^{56} having secured to it by a key a^{58} a grooved collar or ring a^{59} . The grooved collar or ring a^{59} (shown separately in Figs. 7, 8, and 9) is provided with a projection a^{60} , constituting one of the cams, which is adapted 80 to engage the crank or arm a^{51} , and the lever a^{55} is also provided with a thickened or cam surface a^{61} , (see Fig. 15,) which cam a^{61} is also adapted to be brought into engagement with the crank or arm a^{51} . The grooved collar or 85 ring a^{59} is adapted to be moved longitudinally on the sleeve a^{56} in the direction indicated by the arrow 40, Figs. 6 and 15, so as to bring its cam-surface a^{60} into line with the crank or arm a^{51} and to be moved in the direction opposite to that indicated by the arrow 40, so as to remove the cam projection a^{60} , which constitutes the tipping device for the latch-arm a^{34} , from in line with the crank or arm a^{51} . These movements of the grooved collar 90 a^{59} and its cam a^{60} in accordance with this invention are automatically effected by the pressure of the gas admitted into the admission-valve cylinders, so that when the gas is of a constant or high pressure the cam a^{60} 100 may be moved out of line with the crank or arm a^{51} in the direction opposite to that indicated by the arrow 40—namely, into the position shown in Fig. 15—and when the pressure of the gas is reduced and it is desired the 105 engine should operate under variable pressure the cam a^{60} will be moved into line with the crank or arm a^{51} and in the direction indicated by the arrow 40 and into the position shown in Fig. 6. The mechanism by which 110 these movements of the sleeve a^{56} and its attached cam a^{60} are effected may and preferably will be such as will now be described.

The grooved collar a^{59} is adapted to be engaged by a yoke a^{70} , (see Fig. 3,) having an arm 115 a^{71} , which is pivoted, as at a^{72} , on top of the valve-casing a and is connected at its upper end by a link or rod a^{73} to a crank or arm a^{74} , fast on a rock-shaft a^{75} , supported in suitable bearings a^{76} on top of the engine-cylinder A 120 and provided at one end with a crank or arm a^{80} , to which is pivotally connected a piston-rod a^{81} (see Fig. 3) of a piston a^{84} , (see dotted lines, Fig. 3,) contained in a cylinder a^{85} , provided at its lower end with a gas-inlet pipe 125 a^{86} , which communicates, as herein shown, by a branch pipe a^{87} with a chamber a^{88} , with which directly communicate the valve-casings a and a^2 , and which chamber is provided, as shown in Fig. 3, with a high-pressure supply-pipe a^{90} and a low-pressure supply-pipe a^{91} , the high-pressure supply-pipe a^{90} being provided, as herein shown, with a throttle-valve a^{92} , and the low-pressure supply-pipe 130

a^{91} being provided with an automatically-operated valve a^{93} . The main supply-pipe a^{90} is adapted to be connected with a suitable reservoir containing gas or gas and air under high pressure, and the pipe a^{91} is adapted to be connected with a suitable reservoir containing gas or gas and air under a lower pressure. These reservoirs are not herein shown, as they form no part of my invention and are well known.

From the above description it will be seen that the pressure in the cylinder a^{85} acting on the under side of the piston a^{84} is the same as that in the chamber a^{88} and that when the gas of high pressure is supplied to the chamber a^{88} it is admitted to the cylinder a^{85} and acts to move the piston a^{84} upward in the direction indicated by the arrow 60, Fig. 3, which upward movement rocks the shaft a^{77} in a rearward direction and by means of the link a^{75} draws the grooved collar a^{59} and its attached cam a^{60} into the position shown in Fig. 15—that is, so that the cam a^{60} is moved out of line with the crank or arm a^{51} , and as long as the pressure of the gas is sufficient to keep the piston a^{85} elevated the cam a^{60} will be held in its withdrawn position with relation to the crank or arm a^{51} and the admission and exhaust valves of the engine will be operated from the main eccentric through the wrist-plate a^{45} . When the cam a^{60} is withdrawn from in line with the crank or arm a^{51} , the engine is operating as a constant-pressure engine and the gas or gas and air admitted into the cylinder behind the piston when the latter is at one end thereof is exploded by means of an igniter B, which may be of any usual or suitable construction and communicating with the outlet port or passage b (see dotted lines, Fig. 1) from the valve-easing a. The valve of the igniter B has connected to its valve-rod b' (see Fig. 3) a piston b², located in a cylinder b³, provided at its upper end with a gas-inlet pipe b⁴, which is connected to the pipe a⁸⁶, so that high-pressure gas may be admitted into the cylinder b³ above the piston b² and force the same downward against the action of a spring b⁵, located in the said cylinder. The downward movement of the piston b² by the high-pressure gas serves to keep the igniter-valve constantly open as long as the engine is working as a constant-pressure engine. When, however, the pressure of the gas is diminished, the spring b⁵ acts on the piston b² and closes the igniter-valve, and the latter is then opened at the proper time to enable the engine to be worked as a variable-pressure engine, as will be described.

When the engine has been started as a constant-pressure engine and is running in the proper manner, the throttle-valve a⁹² may be closed and the proper connection made with the reservoir containing the gas and air under low pressure, which is admitted into the chamber a⁸⁸ through the pipe a⁹¹, the valve a⁹³ being automatically opened by the pres-

sure of the gas and held open against a stop b⁶. (Shown by dotted lines in Fig. 3.) The diminution of gas-pressure in the chamber a⁸⁸ is immediately felt in the cylinders a⁸⁵ b³, and as a result the piston a⁸⁴ is permitted to descend by gravity in the present instance and the piston b² is moved upward by the spring b⁵. When the pressure in the cylinder a⁸⁵ has been sufficiently reduced, the piston a⁸⁴ descends and moves the rock-shaft a⁷⁷ and by means of the link connection a⁷⁵ and yoke a⁷⁰ moves the cam-collar a⁵⁹ in the direction indicated by the arrow 40 and places the cam or tipping device a⁶⁰ into line with the crank or arm a⁵¹, (see Fig. 6,) so that on every alternate revolution of the main shaft a⁷ the cam a⁶⁰ is engaged with the crank or arm a⁵¹ and is moved in the direction indicated by the arrow 20, Fig. 5, so as to carry the crank or arm a⁵¹ and the latch-arm a³⁴ in the direction indicated by the arrow 80, Fig. 5, which will trip or remove the latch from operative position with relation to the head a³² on the bolt a³¹, and thereby enable the sleeve a³⁹ to be rocked on its bearing 2 without engaging the latch a³⁴ with the head a³² of the bolt, and consequently without lifting the valve a⁴. The collar a⁵⁹ may be rocked at alternate reciprocations of the piston A², as herein shown, by one of two eccentrics b²⁰ b²¹, mounted on a shaft b²², suitably supported in the framework of the engine and provided with a large gear b²³, which meshes with a pinion or gear b²⁴ of one-half its size, fast on the main shaft A⁷, so that the shaft b²² may make one revolution to every two revolutions of the main shaft. In the present instance I have represented the eccentric b²⁰ as operatively connected to the collar a⁵⁹, so as to rock the same, the said eccentric being joined by a link or rod b²⁵ to one end of a lever b²⁶, pivoted at b²⁷ and having its other end joined by a link or rod b²⁸ to the crank or arm a⁵⁷ of the collar a⁵⁹. The eccentric b²¹ is connected in a similar manner by link b²⁹, lever b³¹, pivoted at b³², and link or rod b³³ to the crank a⁵⁷ of the collar a⁵⁹, governing the operation of the admission-valve a⁵ at the opposite end of the cylinder A.

The eccentrics b²⁰ b²¹ constitute the auxiliary or variable eccentrics and are connected to the cranks a⁵⁷, which govern the operation of the exhaust-valves a⁶ a⁷ at the opposite ends of the cylinder A, the crank a⁵⁷ for the exhaust-valve a⁷ being connected, as herein shown, by link b⁴⁰ and lever b⁴¹ to the rod b²⁸, while the crank a⁵⁷ for the exhaust-valve a⁶ is connected to the rod b³³.

From the above description it will be seen that in the double-acting engine herein shown the admission-valve a⁴ at one end of the cylinder A and the exhaust-valve a⁷ at the opposite end of said cylinder are controlled by the same eccentric b²⁰, substantially simultaneously, while the admission-valve a⁵ and exhaust-valve a⁶ are simultaneously controlled by the eccentric b²¹. The admission-valves

$a^4 a^5$ are also operatively connected to the governor G, which may be of any usual construction and which, as herein shown, has its movable sleeve b^{60} joined by a link b^{61} to a 5 crank b^{62} on a rock-shaft b^{63} , having a crank b^{64} , which is joined by a rod or link b^{65} to the lever a^{55} , the said lever having the cam a^{61} , as shown in Fig. 3, an arm b^{66} , joined by a 10 link b^{67} to the lever a^{55} for the admission-valve a^4 . This connection with the governor enables the amount of gas admitted into the cylinder A to be controlled according to the speed of the engine, for when the speed of the engine is normal the cam a^{61} remains 15 inactive with relation to the arm a^{51} , but when the speed becomes excessive the said cam is brought into position to act on the arm a^{51} , and thereby disengage the latch-arm a^{34} from the crank-arm a^{30} before the valve a^4 has been 20 opened to its fullest extent, consequently diminishing the amount of gas admitted into the cylinder, and thereby reducing the speed to normal, and when this normal condition has again been attained the valve a^4 is opened 25 wide by the latch-arm a^{34} . When the engine is running as a variable-pressure engine, it is required that the valves for the igniters B B' should be operated at the proper time, which is effected by placing the said igniter-valves 30 under the control of the eccentrics $b^{20} b^{21}$. The connection between the eccentrics $b^{20} b^{21}$ and the igniter-valves may and preferably will be accomplished as herein shown and as will now be described.

35 Referring to Figs. 1, 2, and 3, the levers b^{81} have connected to them one end of rods or links $b^{80} b^{81}$, joined at their opposite end to levers $b^{82} b^{83}$, pivoted, as at $b^{84} b^{85}$, and having arms $b^{86} b^{87}$, which have a sliding engagement 40 with the valve-rods $b' b'^a$ of the igniter-valves and which are adapted to engage collars b^{90} b^{91} on said valve-rods to open the igniter-valves against the action of the springs b^5 . The collars $b^{90} b^{91}$ are placed on or secured to the valve-rods, so that the arms $b^{86} b^{87}$ may be 45 moved up and down on the valve-rods without engaging said collars when the engine is running as a constant-pressure engine, the pressure admitted into the cylinders b^3 above the pistons b^2 moving the collars $b^{90} b^{91}$ down beyond the range of movement of the arms $b^{86} b^{87}$; but when this pressure is reduced the 50 springs b^5 close the igniter-valves and bring the collars $b^{90} b^{91}$ up into position to be engaged by the arms $b^{86} b^{87}$, which operate at the proper time to open the igniter-valves and explode the charge compressed within the cylinder A, as is now practiced in four-cycle gas-engines.

55 60 I have herein shown and described one mechanical construction and arrangement whereby a gas-engine may be started as a constant-pressure engine and be automatically converted by diminution of pressure into a variable-pressure engine; but I do not desire to limit my invention to the precise mechanical construction shown. Furthermore, the inven-

tion herein described is applicable to either a single-acting or a double-acting engine, and in the double-acting engine the admission-valve at one end and the exhaust-valve at the other end of the cylinder work in pairs. The valve-casings $a a^2$ are provided with suitable devices to prevent flashing back, and in the present instance these devices are shown 75 as a series of pencils, rods, or pins f , projecting from a cap or plate f' , adapted to be bolted to the top of the valve-casings, the said pencils or rods being arranged in circles, as shown in Figs. 10 and 11, and having the 80 same effect as the well-known wire-gauze or perforated plate to prevent the passage of the flame.

I claim—

1. In a gas-engine, the combination of the 85 following instrumentalities, viz: a cylinder provided with a gas-admission valve, and with an exhaust-valve, mechanism to actuate said valves, and means responsive to the pressure under which the engine is working to automatically operate said valve-actuating mechanisms and convert the engine automatically from a constant-pressure engine into a variable-pressure engine, substantially as described.

90 2. In a gas-engine, the combination of the following instrumentalities, viz: a cylinder provided with a gas-admission valve and with an exhaust-valve, actuating mechanisms for said valves, a main shaft, an eccentric on said 95 shaft connected to said valve-actuating mechanism to operate it at every revolution of the main shaft, an auxiliary eccentric, and mechanism connected to said auxiliary eccentric and co-operating with said valve-actuating 100 mechanism, and means operated by the pressure of the gas admitted into said cylinder to render active the mechanism connected to the auxiliary eccentric and thereby control the 105 operation of the valves, substantially as described.

110 3. In a gas-engine, the combination of the following instrumentalities, viz: a cylinder provided with a gas-admission valve and with an exhaust-valve, actuating mechanisms for 115 said valves, mechanism operated by a predetermined pressure to place the said valve-actuating mechanism in condition to be operated to open the valves at each complete reciprocation of the piston in said cylinder, and responsive to a diminution from said predetermined pressure to place said valve mechanism in condition to be operated to open the 120 valves at alternate reciprocations of said piston, substantially as described.

125 4. In a gas-engine, the combination of the following instrumentalities, viz: a cylinder provided with a gas-admission valve and with an exhaust-valve, a gas-igniter controlling the ignition of the gas admitted into said cylinder, valve-actuating mechanisms for said admission and exhaust valves, a wrist-plate connected to said valve-actuating mechanisms, a main eccentric connected to said wrist-plate,

- means coöperating with the valve-actuating mechanisms and responsive to a predetermined pressure to render said valve mechanisms responsive to each revolution of the said main eccentric, an auxiliary eccentric, and means connected to said auxiliary eccentric to render the valve-actuating mechanism responsive only to alternate revolutions of the main eccentric, substantially as described.
5. In a gas-engine, the combination of the following instrumentalities, viz: a cylinder provided with a gas-admission valve and with an exhaust-valve, actuating mechanisms for said valves, each comprising a rock-shaft ²⁰ connected to the valve and provided with a crank or arm ³⁰ having a projection ³², a sleeve ³³, provided with a crank ³³, a rock-shaft ³⁶ carried by said crank and provided with a latch or arm ³⁴ to engage the projection ³², and with an arm ³¹, a sleeve ³⁶ provided with a crank or arm, a collar keyed-on the sleeve ³⁶ and provided with a cam, means to rock the sleeve ³³ to lift the valve, means responsive to the pressure of the gas to move the said collar on the sleeve ³⁶ to move its attached cam into and out of line with the crank or arm ³¹, and means to rock the sleeve ³⁶, substantially as described.
6. In a gas-engine, the combination of the following instrumentalities, viz: a cylinder provided with a gas-admission valve and with an exhaust-valve at its opposite ends, a gas-igniter coöperating with each of said gas-admission valves, a valve-actuating mechanism for each of said admission and exhaust valves, a piston in said cylinder, a main shaft to which said piston is connected, a main eccentric on said main shaft, a wrist-plate connected to said main eccentric and to which the actuating mechanisms for said valves are connected, auxiliary eccentrics driven from the main shaft and revolving at a slower speed than the main eccentric, a tripping device for each of said valve-actuating mechanisms operated by said auxiliary eccentrics, means to operatively connect the valves of said igniters to said auxiliary eccentrics, and means responsive to the pressure of the gas admitted into said cylinder to render the tripping device active or inactive according to said gas-pressure, a second tripping device for the gas-admission valves, and a governor connected to said second tripping device substantially as described.
30. following instrumentalities, viz: a cylinder provided with a gas-admission valve and with an exhaust-valve at its opposite ends, a gas-igniter coöperating with each of said gas-admission valves, a valve-actuating mechanism for each of said admission and exhaust valves, a piston in said cylinder, a main shaft to which said piston is connected, a main eccentric on said main shaft, a wrist-plate connected to said main eccentric and to which the actuating mechanisms for said valves are connected, auxiliary eccentrics driven from the main shaft and revolving at a slower speed than the main eccentric, a tripping device for each of said valve-actuating mechanisms operated by said auxiliary eccentrics, means to operatively connect the valves of said igniters to said auxiliary eccentrics, and means responsive to the pressure of the gas admitted into said cylinder to render the tripping device active or inactive according to said gas-pressure, a second tripping device for the gas-admission valves, and a governor connected to said second tripping device substantially as described.
35. by said auxiliary eccentrics, means to operatively connect the valves of said igniters to said auxiliary eccentrics, and means responsive to the pressure of the gas admitted into said cylinder to render the tripping device active or inactive according to said gas-pressure, a second tripping device for the gas-admission valves, and a governor connected to said second tripping device substantially as described.
40. by said auxiliary eccentrics, means to operatively connect the valves of said igniters to said auxiliary eccentrics, and means responsive to the pressure of the gas admitted into said cylinder to render the tripping device active or inactive according to said gas-pressure, a second tripping device for the gas-admission valves, and a governor connected to said second tripping device substantially as described.
45. by said auxiliary eccentrics, means to operatively connect the valves of said igniters to said auxiliary eccentrics, and means responsive to the pressure of the gas admitted into said cylinder to render the tripping device active or inactive according to said gas-pressure, a second tripping device for the gas-admission valves, and a governor connected to said second tripping device substantially as described.

sive to the pressure of the gas admitted into said cylinder to render the tripping device active or inactive according to said gas-pressure, substantially as described.

7. In a gas-engine, the combination of the following instrumentalities, viz: a cylinder provided with a gas-admission valve and with an exhaust-valve at its opposite ends, a gas-igniter coöperating with each of said gas-admission valves a valve-actuating mechanism for each of said admission and exhaust valves, a piston in said cylinder, a main shaft to which said piston is connected, a main eccentric on said main shaft, a wrist-plate connected to said main eccentric and to which actuating mechanisms for said valves are connected, auxiliary eccentrics driven from the main shaft and revolving at a slower speed than the main eccentric, a tripping device for each of said valve-actuating mechanisms operated by said auxiliary eccentrics, means to operatively connect the valves of said igniters to said auxiliary eccentrics, and means responsive to the pressure of the gas admitted into said cylinder to render the tripping device active or inactive according to said gas-pressure, a second tripping device for the gas-admission valves, and a governor connected to said second tripping device substantially as described.

8. In a gas-engine, the combination of the following instrumentalities, viz: a cylinder provided with a gas-admission valve and with an exhaust-valve, actuating mechanisms for said valves, and tripping devices for said admission and exhaust valves responsive to the pressure of gas employed to run the engine to automatically change the engine from a constant-pressure to a variable-pressure engine, substantially as described.

In testimony whereof I have signed my name to this specification in the presence of two subscribing witnesses.

LOUIS J. HIRT.
